UNITED STATES PATENT OFFICE

GUSTAVUS A. HANCOCK, OF OAK LANE, PENNSYLVANIA

DESIGN FOR A HEARTH BROOM

Application filed September 26, 1929. Serial No. 32,875. Term of patent 3½ years.

To all whom it may concern:

Be it known that I, GUSTAVUS A. HANCOCK, a citizen of the United States, residing at Oak Lane, in the county of Philadelphia and State of Pennsylvania, have invented a new, original, and ornamental Design for Hearth Brooms, of which the following is a specification, reference being had to the accompanying drawing, forming part thereof.

In the drawings, Fig. 1 is an elevation of a broom showing my new design; Fig. 2 is an elevation showing the opposite side of the broom from that shown in Fig. 1 and Fig. 3 is an end view of the broom.

The essential feature of my design consists of a hearth broom formed of a bunch of broom corn having a substantially cylindrical portion with a flaring portion at one end and a tapering portion at the other end thereof, the cylindrical portion being bound by spaced sets of circumferential bands and the tapered portion having a looped handle projecting therefrom and twisted back on the broom.

I claim:

The ornamental design for a hearth broom as shown and described.

GUSTAVUS A. HANCOCK.
